UNITED STATES PATENT OFFICE.

GEORGE B. KEPLINGER, OF CHICAGO, ILLINOIS, ASSIGNOR TO CRUVER MFG. CO., OF CHICAGO, ILLINOIS, A CORPORATION OF ILLINOIS.

PERMUTATION LOCK FOR RECEPTACLES.

1,403,328.

Specification of Letters Patent. Patented Jan. 10, 1922.

Application filed September 4, 1917. Serial No. 189,551.

To all whom it may concern:

Be it known that I, GEORGE B. KEPLINGER, citizen of the United States, residing at Chicago, in the county of Cook and State 5 of Illinois, have invented certain new and useful Improvements in Permutation Locks for Receptacles; and I do hereby declare the following to be a full, clear, and exact description of the invention, such as will enable others skilled in the art to which it appertains to make and use the same.

This invention relates to improvements in a receptacle equipped with a removable cover constituting a portion of a permutation lock which normally locks the cover in place upon the receptacle and against removal, and more particularly to small receptacles adapted to be carried in the pocket. The main object of the invention is to provide 15 a receptacle of the character defined in which the locking element occupies a comparatively small space thereby particularly adapting such receptacle for use as a pocket savings bank or the like.

25 A further object of the invention is to provide a receptacle of the character defined which may be easily and cheaply manufactured, which presents a very neat appearance.

30 The invention consists in the features of construction and combinations of parts hereinafter fully described and particularly claimed.

In the accompanying drawings illustrating 35 a suitable embodiment of the invention:

Figure —1— is a perspective view of the receptacle constructed in accordance with the invention.

Figure —2— is a diametric section of the 40 same.

Figure —3— is a fragmentary detail view showing a guard spring employed.

Figure —4— is a fragmentary detail section showing a detail of construction.

45 Figure —5— is a perspective view of the receptacle with the cover removed.

Figure —6— is a perspective view showing the inner face of the cover.

50 Figures 7, 8 and 9 are detail sectional perspective views showing portions of the permutation lock mechanism.

Figure —10— is a detail perspective view of one of the tumblers employed.

55 Figure —11— is a similar view of another of the tumblers employed.

Figure —12— is a view similar to Figures

—10— and —11— showing a ring employed for transmitting movement of the cover to one of the tumblers

The receptacle comprises a cylindrical 60 wall 1 to which a bottom portion 2 is permanently secured in any suitable manner. At the mouth of the receptacle 1 there is formed an annular inwardly extending flange 3 having a cylindrical lip 4 extending toward the bottom 2. The said flange 3 and lip 4 coact with the wall 1 to provide an annular channel in which the lock elements or rings 5 and 6 are adapted to be received.

70 The said flange 3 and lip 4 are provided preferably with three recesses 7 extending radially and spaced equidistantly from each other, and the said lock elements 5 and 6 are similarly provided with recesses 8 and 9 respectively, adapted to register with each other and with the recesses 7 when the cover is to be removed and replaced.

75 The said cover comprises an outer concavo-convex element 10 which is provided at 80 its periphery with a graduated scale 11 having a certain number of divisions which, in the instance illustrated, total one hundred, every tenth one of which is numbered. The said element 10 receives a disc 12 having a 85 central dished portion 13. The edge portion of the element 10 is crimped over the circumferential edge of the disc 12, the latter being preferably slightly corrugated, or similarly roughened so as to bite into the overhanging flange 14 of the outer disc or its celluloid or other covering so as to securely hold the disc 12 and the cover member 10 against relative rotation. The disc 12 is provided with three equally spaced L-shaped 90 projections 15 adapted to register with and pass through the recesses 7, 8 and 9 when the latter are in register with each other for mounting and removing the cover. The free end portions of the projections 15 project 95 radially outwardly and underneath the flange 3 and its lip 4 when said cover is turned relatively to the receptacle body through an arc less than one hundred twenty degrees.

100 The permutation lock includes, as aforesaid, the tumbler 5 which comprises a ring equipped with three outwardly extending arcuate flanges 16, 17 and 18, which are relatively so disposed that one of the recesses 8 110 extends into each of said flanges, but at different points between a, b and c the ends of

the same. In this manner three arcuate spaces of respectively different lengths and differently positioned with respect to the recesses 8 are formed exteriorly of the ring 5, the purpose of which will hereinafter appear. The ring 5 has one end flush with one face of each of the flanges 16, 17 and 18, the other end portion being parallel with but spaced therefrom so as to provide an arcuate shoulder 19 contiguous to each of the arcuate flanges and on opposite sides of each of the recesses 8. Preferably the ring 5 is slightly distorted so that when it is mounted within the channel formed by the flange 3 and its lip 4, said ring will frictionally engage the said lip 4 and resist free rotation relatively to the same. The radial distance from the inner face of the ring 5 to the outer edge of each of its arcuate flanges is less than the width 20 of the annular channel in which said ring lies. Said ring is so positioned that the arcuate flanges thereof abut against the lower face of the flange 3, and the inner face of the ring 5 engages the outer circumferential 25 face of the lip 4.

The tumbler 6 consists of a flat ring of metal having an annular flange 20 which projects from one face of said ring a distance substantially equal to the thickness 30 of the arcuate flanges of the ring 5. The ring 6 is provided with bayonet slots 21 which provide free spring tongues 22 adapted to be bent slightly outwardly for engagement with the inner face of the cylindrical wall 1 of the receptacle for providing a yielding resistance to the free rotation of said ring 6. The depth of the flange 20 and ring 6, and also the depth of the ring 5, is preferably substantially equal to 40 the depth of the lip 4 of the flange 3, or of the channel bordered by said lip so that when said tumblers are mounted in said channel they completely fill the same. The ring 6 is further provided with two pairs of 45 projections 23 and 24. The former project from the same face of the said ring as the flange 20, while the latter project from the other or exposed face of said ring when the latter is mounted in the channel aforesaid.

50 Associated with said tumblers 5 and 6, and the projections 15 of the cover, is a small ring 25 which fits relatively snugly against the inner circumferential face of the wall 1 of the receptacle, and is provided 55 with a small annular flange 27 normally lying in surface contact with the outer circumferential edge portion of the exposed face of the ring 6. The said ring 25 is held in place, as are also the tumblers 5 and 6, by 60 means of the split ring 28 of wire which is sprung into the annular groove or bead 29 between the ends of the wall 1 of the receptacle. The ring 25 is provided with a tongue 30 projecting radially of the receptacle and over the edge of the lip 4. Said

tongue may be suitably secured to the ring 25, as for example by means of the lugs 31 punched up from the flange 27 and bent over to engage opposite side edges of said tongue 30. The latter terminates at its other end in 70 a lip 32 which partially overhangs the said split ring 28.

Suitably formed in the wall 1 of the receptacle is a small arrow-head or indicator 75 33 which is adapted to indicate on the graduations of the scale 11 of the cover as the latter is rotated relatively to the receptacle body.

The operation of the device is as follows:

The tumblers 5 and 6 are first turned so 80 that the recesses 8 and 9 therein register with the recesses 7 in the flange 4. The tongue 30 of the ring 25 is turned so as to lie between two of the recesses 7. The cover is then mounted on the receptacle by passing the 85 projections 15 through the registering recesses 7, 8 and 9, and by then turning the cover through a short arc it becomes non-removable from the receptacle. To lock the cover against such removal the same is 90 turned continuously in either direction until one of the projections 15 engages the tongue 30 and the latter engages one of the projections 24 between the two of which it must lie, thereby turning the tumbler 6 so that the 95 recesses 9 therein are thrown out of register with the recesses 7. By still continuing the rotation of the cover in the same direction one of the projections 23 will be thrown into engagement with one of the arcuate flanges 100 18 of the ring 5, and the latter will then be turned through an arc to throw the recesses 8 out of register with the recesses 7. This rotation of these several parts, namely: the 105 cover and the tumblers 5 and 6 may be continued until the tongue 32 strikes a projection 34 on the inner circumferential wall 1 of the receptacle bordering the coin slot 35 therein. In the instance illustrated there are two of said projections 34 for limiting 110 the rotation of the ring 25 in respectively opposite directions, and which also serve as means for securing a spring 36 in place past which coins are forced, and which prevents removal of said coins in a well-known 115 manner. When this position of the several parts aforesaid has been attained the indicating hand or pointer 33 will register with a given graduation on the scale or dial 11. During rotation of the cover in the aforesaid 120 direction it will have turned the tumbler 6 through a predetermined arc, and the tumbler 5 through a different predetermined arc, that arc being determined in the last-named instance by the distance separating the outer 125 ends of the projections 23, and by the length of the arc separating opposed ends of the two arcuate flanges 16, 17 or 18 between which said projections 23 lie. The arcuate movement of the tumbler 6 to the said posi- 130

tion will be the arc of movement of the ring 5 plus the arc of movement necessary to bring one of the projections 23 into engagement with one of the arcuate flanges of the ring 5 plus the length of the arc normally separating the tongue 30 from the projection 24 toward which it is to be moved plus the arc necessary to bring the nearest projection 15 of the cover into contact with the tongue 30 after said projections 15 have passed through the registering recesses 7, 8 and 9. To reopen the receptacle it now becomes necessary to turn the cover in the opposite direction from that in which it has been primarily turned through the last-named arc so as to return the ring 5 to its first-named position. To accomplish this it is, of course, necessary that the cover be turned through an arc of slightly less than one hundred twenty degrees in order to bring another of the projections 15 into contact with the opposite edge of the tongue 30 from that first engaged. After the last-named projection has been brought into engagement with the opposite edge of the tongue 30 the ring 25 must be turned until the tongue 30 strikes the other of the projections 24 between which it lies. After this the ring 6 will rotate with the ring 25 until the other of the projections 23 engages an arcuate flange of the ring 5, and thereafter both ring tumblers 5 and 6 are rotated with the ring 25. When they have been rotated through the first-named arc the recesses 8 of the ring 5 will again be brought into register with the recesses 7 of the flange 4. At this time, however, the recesses 9 of the ring 6 will not be in register with said recesses 7 and 8, and to bring the same into register therewith it is necessary to again reverse the direction of rotation of the cover 10 until the first-named projection 15 shall again engage the first-named edge of the tongue 30. Then the ring 25 will rotate with the cover until said tongue 30 again engages the first-named projection 24, and by then continuing the rotation through a given arc the recesses 9 will be brought into register with the recesses 7 and 8. The cover must then be again reversed through the short arc separating the last-named side edge of the tongue 30 from the nearest contiguous registering recesses, whereupon the cover may be removed.

Assuming, for example, that after the cover has been placed on the receptacle it is necessary to turn it through an arc equal to seven graduations of the dial 11 before the side edge of the tongue 30 is engaged by a projection 15, then the last-named reverse rotation through the same arc will again bring the projections 15 into register with said recesses and permit the cover to be removed. If, however, the rotation of the cover in the same direction is continued after the said projection 15 engages one side

edge of the tongue 30, and until said tongue engages one of the projections 24, and assuming this to be an arc equal to fifteen graduations of the dial 11, and the further rotation in the same direction of the cover necessary to bring the first projection 23 into engagement with an arcuate flange of the ring 5 requires a further rotation through an arc equal to ten of the graduations of the dial, then obviously in order to again bring the recesses 9 into register with the recesses 7 and 8, it will be necessary to first turn the ring 6 through an arc equal to the last-named ten graduations plus fifteen graduations, or a total of twenty-five. This is accomplished, of course, by reversing the direction of rotation of the cover until another of the projections 15 engages the opposite side face of the tongue 30. This, as before stated, requires rotation of the cover through an arc somewhat less than one hundred twenty degrees. From this point the cover is rotated through an arc of twenty-five degrees, whereupon the recesses 9 will again register with the recesses 7 and 8, and then by again reversing the rotation of the cover through an arc of seven graduations as aforesaid, the projections 15 will again register with the registering recesses permitting the cover to be removed. In the last-named operation it will be observed that the position of the ring 5 was not changed from normal.

The combination may be changed by varying the position of the projections 23 with respect to the arcuate flanges 16, 17 and 18, that is to say, if said projections are disposed in the arcuate space between the flanges 16 and 18, the combination will be different from that which would be controlling were said projections disposed between the arcuate flanges 17 and 18, and likewise 16 and 17. Without changing the arcuate length of the respective flanges 16, 17 and 18, or the arcuate distance separating the active ends of the projections 23 any one of six combinations may be utilized, three of them reading to the right, and three to the left. Whether the combination reads right or left, (that is to say, whether the primary unlocking rotation of the cover shall be to the right or to the left) is determined by the position of the tongue 30 with respect to the registering recesses disposed between the projections 24 of the ring 6, as will be doubtless readily understood.

The combination is further varied by varying the position of the dial with respect to the projections 15. For example, in one case the graduation "60" of the dial may register radially with one of the projections 15, and in another case the graduation "70" may register therewith. The numerals of the whole combination would then vary by ten in the two cases.

The stops 34 simplify the operation in that they always constitute a basis for determining the combination of each receptacle to the particular arcuate space in 5 which the projections 23 lie. If in a certain lot of receptacles they lie in the largest arcuate space between the arcuate flanges of the ring 5 a person thoroughly familiar with the operation need only turn the cover 10 to the right as far as it will turn. He will then read which of the graduations of the dial registers with the indicating hand, and will know, for example, that in attaining this position the cover was rotated to the 15 right through an arc of forty graduations from its entering position, and that he must turn the same to the left through an arc of eighty-five graduations to bring the recesses of the tumbler 5 into register with 20 the recesses 7, and then must again rotate the cover to the right through an arc of fifty-two graduations to bring the recesses of the ring 6 into register with recesses 7, and that by then turning the cover seven 25 graduations to the left, the cover may be removed.

Thus one lot of said receptacles sold to a bank will all open on the foregoing combination, though the ordinals of the dial 30 graduations may not be alike in any two of said lot. The banker will easily be able to open any of the banks when presented for the purpose by knowledge of the foregoing.

It will be noted that the tumbler rings 5 35 and 6 are relatively so arranged as to be only lightly in surface contact with each other so that the rotation of one thereof will not be frictionally transmitted to the other, this being very important and obviating the interposition of washers between the rings. It 40 will also be seen that each of the rings presents a surface flush with the inner edge of the lip 4 of the flange 3 so that even though the recesses of the ring 6 register with the 45 recesses 7, the operator will not be able to ascertain this and thus learn one of the figures of the combination by pulling the cover partly off when such registry occurs.

While I have shown the preferred embodiment of the invention in the accompanying drawings, it will be understood, of course, that the same may be changed and varied in details without departing from the invention as defined in the appended claims.

55 I claim as my invention:

1. A permutation lock for receptacles comprising a cylindrical receptacle body and a removable cover therefor rotatable relatively to the body, a plurality of L-shaped projections on the inner face of the cover having their free end portions extending radially outwardly, an L-shaped inwardly extending flange at the mouth of the receptacle having its free end portion opposing the receptacle body and provided with radial re-

cesses corresponding in number, size and relative location with the projections on the cover, the latter adapted to pass through said recesses and engage the lower edge of the L-shaped flange when the cover is turned, 70 a plurality of permutation lock-elements mounted to rotate in the channel of said L-shaped flange and having recesses adapted to register with each other and said recesses in said flange to permit mounting and removal of the cover, interengaging formations on said lock elements for limiting their rotation relatively to each other, and a projection on one of said lock elements adapted to be engaged by projections of the cover 80 for effecting rotation thereof with said cover.

2. A permutation lock for receptacles comprising a cylindrical receptacle body and a removable cover therefor rotatable relatively to the body, a plurality of L-shaped projections on the inner face of the cover having their free end portions extending radially outwardly, an L-shaped inwardly extending flange at the mouth of the receptacle having its free end portion opposing the receptacle body and provided with radial recesses corresponding in number, size and relative location with the projections on the cover, the latter adapted to pass through 90 said recesses and engage the lower edge of the L-shaped flange when the cover is turned, a plurality of permutation lock-elements mounted to rotate in the channel of said L-shaped flange and having recesses adapted 100 to register with each other and said recesses in said flange to permit mounting and removal of the cover interengaging formations on said lock elements for limiting their rotation relatively to each other, and a projection on one of said lock elements adapted to be engaged by projections of the cover for effecting rotation thereof with said cover, and said lock-elements formed for frictionally engaging the body of the receptacle to 110 resist the rotation of said lock-elements relatively to each other and said receptacle.

3. A permutation lock for receptacles comprising a cylindrical receptacle body and a removable cover therefor rotatably relatively to the body, a plurality of L-shaped projections on the inner face of the cover having their free end portions extending radially outwardly, an L-shaped inwardly extending flange at the mouth of the receptacle having its free end portion opposing the receptacle body and provided with radial recesses corresponding in number, size and relative location with the projections on the cover, the latter adapted to pass through 115 said recesses and engage the lower edge of the L-shaped flange when the cover is turned, a plurality of permutation lock-elements mounted to rotate in the channel of said L-shaped flange and having recesses adapted 125 to register with each other and said recesses in said flange to permit mounting and removal of the cover interengaging formations on said lock elements for limiting their rotation relatively to each other, and a projection on one of said lock elements adapted to be engaged by projections of the cover for effecting rotation thereof with said cover, and said lock-elements formed for frictionally engaging the body of the receptacle to 130 resist the rotation of said lock-elements relatively to each other and said receptacle.

to register with each other and said recesses in said flange to permit mounting and removal of the cover, means associated with said receptacle and said lock-elements for

and a projection on the lowermost ring adapted to be engaged by the cover projections for effecting rotation of the several rings by rotating said cover.

5 removably holding the latter in said channel in proper position relatively to each other, interengaging formations on said lock elements for limiting their rotation relatively to each other, and a projection on one 10 of said lock elements adapted to be engaged by projections of the cover for effecting rotation thereof with said cover.

6. A device of the kind specified comprising 70

a receptacle having an inwardly extending annular flange at its mouth provided with a plurality of equally spaced radial recesses, a plurality of rings constituting lock elements rotatably mounted in said receptacle below said flange and all having recesses corresponding in number and location and adapted to register with those of said flange, interengaging projections on the several rings for limiting their relative rotation and for causing them to rotate in unison when said projections are engaged, a cover for said receptacle, L-shaped projections on said cover corresponding in number and location with the recesses of the said flange and adapted to pass therethrough and through the recesses of the several rings when the latter are accordingly positioned, and a projection on the lowermost ring adapted to be engaged by the cover projections for effecting rotation of the several rings by rotating said cover, and each of said rings having yielding parts engaging the receptacle for resisting free rotation of said rings. 95

4. A permutation lock for receptacles comprising a cylindrical receptacle body and a removable cover therefor rotatable relatively to the body, a plurality of L-shaped projections on the inner face of the cover having their free end portions extending radially outwardly, an L-shaped inwardly extending flange at the mouth of the receptacle having its free end portion opposing the receptacle body and provided with radial recesses corresponding in number, size and relative location with the projections on the 20 cover, the latter adapted to pass through said recesses and engage the lower edge of the L-shaped flange when the cover is turned, a plurality of permutation lock-elements mounted to rotate in the channel of said L-shaped flange and having recesses adapted 25 to register with each other and said recesses in said flange to permit mounting and removal of the cover, means associated with said receptacle and said lock-elements for 30 removably holding the latter in said channel in proper position relatively to each other, interengaging formations on said lock elements for limiting their rotation relatively to each other, a projection on one 35 of said lock elements adapted to be engaged by projections of the cover for effecting rotation thereof with said cover, and said lock-elements each having frictional engagement with the receptacle for resisting the rotation 40 of said lock-elements relatively to each other and said receptacle.

5. A device of the kind specified comprising a receptacle having an inwardly extending annular flange at its mouth provided 50 with a plurality of equally spaced radial recesses, a plurality of rings constituting lock elements rotatably mounted in said receptacle below said flange and all having recesses corresponding in number and location and adapted to register with those of said flange, interengaging projections on the several rings for limiting their relative rotation and for causing them to rotate in unison when said projections are engaged, a 55 cover for said receptacle, L-shaped projections on said cover corresponding in number and location with the recesses of the said flange and adapted to pass therethrough and through the recesses of the several rings 60 when the latter are accordingly positioned,

7. In a combination lock for a receptacle, the receptacle having an opening bordered by a channel, a plurality of ring-like permutation lock elements rotatably mounted in the channel, the channel and elements having recesses adapted to be aligned, a cover, channel engaging lugs on the cover adapted to be entered through said recesses for locking the cover on the receptacle, said lock-elements each being formed for yieldingly 100 and frictionally engaging the walls of said channel to resist relative rotation of said lock-elements relatively to each other and to the receptacle. 105

8. In a permutation lock for a receptacle, the receptacle having a circular opening bordered by an inturned flange at the edge of an inwardly projecting flange forming an annular channel, a plurality of ring-like permutation lock-elements mounted for rotation in said channel, one of said elements having an inner flange contacting with said inturned flange and formed to engage same with a frictional engagement to resist free rotation thereof. 110

9. In a permutation lock of the kind described, a substantially circular band having an external flange removed at spaced intervals, the band being distorted out of true circular form, such distortion being 125 permitted by the said removal of parts of said flange, and a cylindrical part fitting within said band and frictionally engaged thereby by reason of its distortion. 125

10. In a permutation lock of the kind de- 130

- 6
- scribed, a ring-like permutation lock-element having an annular flange which is cylindrical in form, a plurality of arcuate projections extending outwardly from one edge of said flange and spaced to provide a plurality of arcuate spaces between them which are of different circumferential lengths, and adapted to receive projections on a co-operating lock member, the placement of the projections in the different arcuate spaces producing variations in the permutations of the lock.
11. In a permutation lock of the kind described, a plurality of ring-like tumblers 15 made of thin sheet metal, a casing having cylindrical walls between which the tumblers are positioned and adapted to rotate, alternate ones of said tumblers respectively, engaging the opposite surfaces of said cylindrical walls with a spring frictional engagement to resist free rotation thereof.
12. In a permutation lock of the kind described, two substantially flat ring-like tumblers made of sheet metal and adapted to 25 nest in a shallow ring like space, cylindrical walls defining the outer and inner sides of said space, spring tongues on one of said tumblers engaging the outer wall, the other tumbler having an inner ring-like portion 30 cut at one or more points and distorted out of true circular form, such distortion being permitted by said cutting, said ring-like portion being conformed to the inner cylindrical wall and engaging the same with a 35 frictional engagement by reason of said distortion.
13. In a permutation lock of the kind described, spaced cylindrical walls and flat 40 parallel walls defining within said walls a shallow annular space, and flat ring-like

tumblers arranged within said space, said tumblers being formed with yielding portions at their edges adapted to frictionally engage the cylindrical defining walls of said space.

45

14. In a permutation lock of the kind described, a tumbler having a ring-like band at its inner edge adapted to engage a cylindrical wall, the band severed at intervals to form notches, the adjacent ends of the portions of the band connected by segments of an outer flat flange whereby the band being distorted out of true circular form in manufacture is by reason of its shape adapted to engage a cylindrical wall with a frictional 50 engagement.

55

15. In a permutation lock of the kind described, outer and inner cylindrical walls and flat end walls defining a substantially enclosed shallow annular space, and two 60 rotatable tumbler rings rotatably arranged within said space, each tumbler ring bearing against both of said end walls whereby it is held against endwise movement.

65

16. In a permutation lock of the kind described, outer and inner cylindrical walls and flat end walls defining a substantially enclosed shallow annular space, and rotatable tumbler rings rotatably arranged within said space and held against endwise movement by said end walls, one of said rings 70 engaging the inner cylindrical wall with a yielding frictional engagement and the other of said rings engaging the outer cylindrical wall with an independent yielding frictional engagement, said frictional engagement in each case being sufficient to prevent any but intentional rotation of the tumbler rings.

75

GEORGE B. KEPLINGER.
